UNITED STATES PATENT OFFICE.

ALDEN R. VAUGHAN, OF PAWTUCKET, RHODE ISLAND.

MAINSPRING-WINDER.

SPECIFICATION forming part of Letters Patent No. 443,881, dated December 30, 1890.

Application filed May 23, 1890. Serial No. 352,904. (No model.)

To all whom it may concern:

Be it known that I, ALDEN R. VAUGHAN, a citizen of the United States, residing at Pawtucket, in the county of Providence and State 5 of Rhode Island, have invented certain new and useful Improvements in Spring-Winders, of which the following, taken in connection with the accompanying drawings, is a specification.

10 The object of my invention is to produce an instrument for removing from and replacing mainsprings in the barrels of clocks, music-boxes, or other instruments where barrels are used for the spring.

15 The invention consists of various details of construction, as hereinafter fully described, and pointed out in the claims.

Referring to the accompanying drawings, Figure 1 is a side view of a mainspring-winder 20 embodying my invention. Fig. 2 is an end view of the same. Fig. 3 is a plan or top view. Fig. 4 is a horizontal section taken on line $x-x$ of Fig. 1. Fig. 5 is a view of the under side. Fig. 6 is a longitudinal vertical section taken 25 on line $y-y$ of Fig. 3. Fig. 6^a is a detail view. Fig. 7 is a vertical transverse section taken on line $z-z$, Fig. 3.

The frame consists of two plates A B, held at the required distance apart by posts or 30 spacer-blocks C, one end of which is tapped or secured to one plate and the other end fitted to receive a screw c, that passes through the other plate. In the center of this frame is secured, but so as to revolve freely, a ratchet-wheel D, through the center of which passes a winding-arbor, shown as a square bar or spindle E, that slides freely, so as to allow the 35 end to be adjusted to any desired width of spring. The lower end of this bar is fitted 40 with a handle F, and the upper end is provided with a round projection e, upon which is secured a collar G, provided with a catch or hook g. This collar I prefer to secure to the end e of the spindle E by means of a screw 45 f, that is of a length equal to the diameter of the end e and is screwed into the same, a hole being formed in the collar G, so that after it has been placed on the spindle the screw is turned so as to cause it to project into the 50 hole in the collar, as shown in Fig. 6^a, thereby holding it in position.

II is a two-armed pawl fulcrumed at its rear

end h between the two plates A B, so as to swing freely, and so that the end of either arm can be thrown into contact with the ratchet-wheel D by means of a spring i, attached at one end to the fulcrum h and at the other end to a pawl-lever I, preferably made of wire bent to the form shown and fulcrumed between the plates A B, the lower portion i' extending a short distance below the bottom plate and formed with an arm i², by which either arm of the pawl can be thrown in or out of gear with the ratchet-wheel by the thumb of the operator while holding the instrument in his hand. The object of this ratchet-wheel and two-armed pawl is to allow the spindle E to be turned in either direction, so as to wind the spring either to the right or left, as required.

J is a sliding block, through which passes a clamp K, a screw k preventing it from falling out of the block, but at the same time allowing a free vertical movement.

L is a screw that passes into the block J 75 for clamping the jaws of the clamp K to the spring when in the required position. The outer end of this screw is provided with a cross-bar or thumb-piece l. In each of the plates A B is formed a slot M, through which 80 the clamp K passes, which can be adjusted in any position in the said slots.

N is a sight-hole formed in the upper plate to allow the operator to see the spring when 85 adjusting the jaws of clamp K.

P are sleeves that pass through both the plates A B, and are provided at their lower ends with cams Q, and their upper ends are screw-threaded and are formed with slots, (preferably four.)

R are screw-threaded caps that fit on the upper ends of each of these sleeves, so that when the caps are turned down the upper ends of the sleeve are forced inward.

S are arms bent at right angles, one end 95 of each passing down through one of the caps R into the sleeve P, and can be adjusted and clamped at any desired height by turning down the cap R. Near the lower end of each of these arms is passed a small pin r, that works in the slots in the upper end of the sleeve, so that they turn with the sleeves, but can be adjusted in height. The outer or free ends of these arms are bent inward, so as to

form a pawl that takes into one of the spaces between the teeth on the spring-barrel. (Shown in dotted lines in Figs. 1 and 3.)

T is a screw secured in the lower plate B 5 between the cams Q. Upon this screw is fitted a clamping-bar U, the upper end of which is provided with a loose collar V, which when the bar U is screwed up tightly clamps the cams Q, thereby holding the arms S firmly 10 in place.

The cams Q are provided with a projection q, (see Fig. 5,) so that when the cams are not clamped the arms S will be prevented from turning beyond a certain distance, as the projections q will come into contact with the screw T.

Each winder is provided with several (preferably three) collars G for various sizes of springs. The collars that are not in use are held between the plates A B, as shown in Fig. 20. A spring-cover W, which swings on one post and snaps over the other post, prevents them from falling out at the end, and there is not room for them to pass between the posts 25 and the end of the pawl H.

The operation is as follows: Supposing it is required to remove a spring from the barrel, the barrel is placed on the winder, as shown in dotted lines, and the arms S adjusted to the 30 proper height for the teeth of the barrel. The handle F is then turned until the catch g engages the spring and the barrel turned until the hook in the barrel which holds the outer end of the spring comes within about one-half inch 35 of the jaws of clamp K. The arms S are then brought in contact with the teeth on the barrel and are thereby clamped by turning the rod U, as before described. The instrument is then grasped with the left hand by the end opposite the arms S with the thumb over one and the forefinger over the other of the ends of the two arms S. Then the handle F is turned until the spring is nearly wound up. This leaves the outer end of the spring so that 40 clamp K can be adjusted to the end of the spring, and when done the jaws of clamp K are set firmly to the spring by means of screw L. The barrel can now be removed by releasing the arms S. Then by means of arm 45 i² the lever I is pushed to the opposite side of pawl H and the handle F is turned up a trifle, which will allow the two-armed pawl H to act on the opposite arm and the spring will unwind. When it is desired to replace the 50 spring in the barrel, it is placed over the collar G and adjusted to hook g. The outer end

is placed in the jaws of clamp K and clamped firmly by screw L. Then the handle F is turned and winds the spring. The barrel can then be placed over the spring and the spring 60 transferred from the winder to the barrel by releasing pawl H, letting the spring down by handle F, and releasing clamp K.

What I claim as my invention is—

1. A spring-winder consisting of two plates 65 of metal connected together by posts, a ratchet-wheel mounted in the center between the plates, an adjustable winding-arbor passing through the ratchet-wheel, a two-armed pawl and means for operating the same, a clamp- 70 ing device for holding the outer end of the spring, and arms for holding the barrel, substantially as set forth.

2. In combination with a spring-winder, means for holding the barrel, consisting of 75 two-bent arms S, sleeves P, having cams Q at their lower ends, caps R, screw T, collar V, and clamping-bar U, arranged and operated substantially as shown and described.

3. In combination with a spring-winder, an 80 adjustable clamp for holding the outer end of the spring, consisting of the sliding block J, clamp K, and screw L, substantially as shown and described.

4. In a spring-winder, the combination of 85 the frame A B C, ratchet-wheel D, an adjustable winding-arbor E, handle F, and collar G with the pawl H, pawl-lever I, and spring i, substantially as set forth.

5. In a spring-winder, the combination of 90 the frame A B C, ratchet-wheel D, an adjustable winding-arbor E, handle F, collar G, pawl H, pawl-lever I, and spring i with the adjustable block J, clamp K, and screw L, substantially as shown and described.

6. In a spring-winder, the frame A B C, bent arms S, sleeves P, cams Q, caps R, screw T, collar V, and clamping-bar U, in combination with the ratchet-wheel D, an adjustable winding-arbor E, handle F, collar G, pawl H, 100 pawl-lever I, spring i, and adjustable block J, clamp K, and screw L, substantially as shown and described.

In testimony whereof I have signed my name to this specification, in the presence of 105 two subscribing witnesses, on this 19th day of May, A. D. 1890.

ALDEN R. VAUGHAN.
